UNITED STATES PATENT OFFICE.

FRANK ANDERSON, OF PEEKSKILL, NEW YORK; ANNIE L. ANDERSON, GILBERT H. ANDERSON, AND HOMER ANDERSON ADMINISTRATORS OF SAID FRANK ANDERSON, DECEASED.

TELEGRAPHY.

SPECIFICATION forming part of Letters Patent No. 449,655, dated April 7, 1891.

Application filed May 31, 1890. Serial No. 353,762. (No model.)

To all whom it may concern:

Be it known that I, FRANK ANDERSON, a citizen of the United States, residing at Peekskill, county of Westchester and State of New York, have made a new and useful invention in the Art of Telegraphy, of which the following is a specification.

My invention relates particularly to a novel method and apparatus whereby telegraphic codes are automatically transmitted and received through the agency of a prepared transmitting-record, and its objects are, first, to cause Morse or analogous characters to be automatically transmitted through the agency of an embossed or indented transmitting fillet or strip; second, to correctly reproduce an actual audible record of a Morse operator's writing; third, to economize time in the various outlying line offices of a telegraphic system where inferior operators may be located; fourth, to furnish an easy and accurate system of educating persons in receiving by sound Morse or analogous telegraphic codes.

Prior to my invention it was old in the art to emboss or indent a paper or analogous fillet or strip with Morse or similar telegraphic characters, and to utilize such an indented or embossed fillet through the agency of levers or analogous devices including an electrical circuit in which was located a receiving-instrument, either electro-magnetic, chemical, or any of the equivalent or well-known types of telegraphic receivers; but with all such constructions, so far as I am aware, it is customary to cause the indented or embossed characters to lift or elevate the circuit-closing lever or part a distance equal to the depth of the indenture or embossment, thereby depending upon the strength of the embossment and the slight depth thereof to cause the necessary contact for telegraphic work. All such devices, so far as I am aware, have failed to meet the demands made upon them, because of the lack of certainty of contact maintained at each closure of the circuit by the embossments for the varied times represented by the dots and dashes which they effect. In my

invention I overcome these difficulties by causing the embossments to simply carry or drag the circuit-closer forward in the direction of motion of the embossed strip or fillet by a dragging contact, and I produce a firmness of contact at the circuit-closing points by placing said contact-points near the free end of a lever having its fixed end pivoted, as will be more fully described in connection with the accompanying drawings, to which reference is now had.

Figure 1 is a side elevational view of the entire apparatus, the electrical circuits being shown in diagrammatical view. Fig. 2 is an end elevational view of the entire apparatus, as seen looking at Fig. 1 from right to left. Fig. 3 is a detail view of the embossed transmitting fillet or strip with a spring-pressed guide for holding it in place. Fig. 4 is an elevational view of a modified form of the apparatus.

Referring now to the drawings in detail, wherein like letters represent like parts wherever used, T is a paper or equivalent fillet or strip, having Morse characters embossed in its face in three lines parallel to each other and prepared by an indenting device invented by myself, and fully described in a prior application filed by me in the United States Patent Office on the 28th day of March, 1890, Serial No. 345,777.

I have shown three rows of indentations in the fillet T; but it is obvious that any number of such rows might be used. I prefer to use a number of such rows, for the reason that they give greater stability to the embossed characters, as will be understood in view of the following description.

The prepared paper fillet T is wound upon a reel R, secured to the frame A of the machine by standard N, and passes under a guide-pulley F, over a pivoted curvilinear bearing-plate D, and finally between a driving-pulley B and grooved frictional pulley C, pivotally secured to the frame by an arm c, and provided with an adjustable spring e', as clearly shown in Figs. 1 and 2, the rows or embossed portions of the fillet being on the

upper side thereof as it passes over the curved arm D. This arm D is pivoted at one end to the frame, and at its free end is provided with a handle d, and has an adjusting-screw E and 5 spring e for regulating its vertical movement.

I is a pivoted transmitting-lever fixedly secured by a spring-support h to a metallic or conducting arm II, electrically connected to the line-wire w, running to a distant or local 10 station, as the necessities of the case require. On the lower end of the arm I is a curvilinear spring k of sufficient width to cover the several rows of embossments on the fillet T. The arm I is also provided with an adjustment- 15 spring e³, connected to an adjusting-screw L, secured to the frame, and carries near its lower end a pair of contact or conducting points, of platinum or other equivalent material, adapted to contact with similar adjustable contacts i i', secured to the frame A, and 20 electrically connected by the wires w' to the split battery BA, joined at its middle through an electrical conductor and switch s to earth at G'. A similar earth circuit is shown in dotted lines with a second switch s' and earth 25 contact G², which may be used when it is desired to transmit currents of one polarity, as will be hereinafter described.

G is a guiding strip or spring pivotally secured to the frame and provided with an adjustment-spring e², its free end being forked, so as to bear on both sides of the embossed record-fillet T, as clearly shown in Fig. 3.

I will now describe in detail the operation 30 of the apparatus: The prepared embossed fillet T having been wound upon the reel R and its free end carried under the guiding-roll F and between the brake-spring G, operating-spring k, and curvilinear guiding-arm D, and 35 finally between the driving-pulleys B and C, with the embossments on the upper side as it lies upon the guiding-arm D, the driving-motor (not shown) attached to the pulley B is set 40 in motion. As an embossment on the fillet T comes in contact with the free end of the 45 spring k, the arm I is drawn forward until contact is made between its forward contact-point and the contact i, and the circuit is held closed for a dot or a dash, as the case may be. 50 During the time that the free end of the spring k is lifted and riding over the embossment a positive impulse is sent from the earth G', switch s, and the right-hand portion of 55 the battery BA, wire w', contact i, arm I to the line-wire w. After the embossment passes under the free end of the spring k, the spring e³ draws the arm I into the position shown in 60 the drawings and a negative impulse is transmitted by the negative portion of the battery 65 BA through the wire w', contact i', arm I to line-wire w. It will thus readily be understood that when the forward end of any embossment strikes the free end of spring k the arm I will be carried forward until a contact 70 is effected with the contact-point i and that the reliability of this contact as to pressure will depend upon the relative positions of the

moving contact on the arm I, the fulcrum of the arm at H, and the distance of the contact from the spring k. The relative position of 75 the arm I and the movable transmitting fillet or strip D is such that it is substantially at right angles to said strip, so that when the latter is drawn forward by the pulley B when rotated in the direction of the arrow the embossed fillet will give to the arm I a dragging or drawing motion, and it is obvious that the amount of this forward motion is independent of the height of the embossment. With this arrangement of parts, therefore, wherein the 80 movable electrical contact or contacts is or are located near the end of a long pivoted arm, I am enabled to give a sure or firm electrical contact with an embossment of very slight depth, a feature which has not been accomplished by devices of this generic type heretofore. In other words, the reliability of the 85 electrical contact is made an element of a forward or dragging motion due to the embossment, of whatever depth, and not dependent 90 upon its height.

In actual practice I find that I am enabled with this arrangement of apparatus to insure transmitting contacts with delicately embossed paper records, which are fully equal 95 to those had in the use of Morse keys by skilled operators. In fact, the apparatus reproduces Morse records made by skilled operators upon the fillet T so accurately that 100 when used receiving-operators, who are accustomed to read their writing in daily use, are unable to distinguish that the operators themselves are not actually transmitting. It will thus be seen that I have devised an apparatus which so accurately reproduces Morse 105 characters that all the peculiarities of individual operators may be correctly obtained, so that actual line-operators at outlying stations may have actual embossed copies of messages transmitted by any operator, and 110 may reproduce them from time to time for the purpose of becoming acquainted with the personal peculiarities of such operator's writing. It is also obvious that my improved apparatus has a very desirable and important 115 use in connection with learners who have only local instruments and no one to transmit or write Morse characters for them, it being understood that embossed messages may 120 be prepared on transmitting strips and unreeled from the reel R at pleasure, the Morse sounder being situated in a local circuit instead of the main line. It will be understood how this may be accomplished if the switch s is disconnected from the ground G' and the 125 switch s' is connected to the ground G², a local sounder (not shown) being connected in a local circuit from the wire w to earth G², under which condition of affairs the apparatus will operate on the closed-circuit principle through the front contact of the arm I and battery BA, or a circuit containing a local battery and sounder might be connected 130 to the frame A and post J in a manner at

once understood by those skilled in the art. The wire-connections are shown without the battery and sounder in Fig. 2.

In Fig. 4 I have shown a modified form of apparatus in which the spring *k* is secured to the arm *I* and bears upon the embossed fillet *T*, carried by an ordinary cylinder, the circuit being opened and closed through point *J* and arm *I* as the embossed fillet *T* draws the spring *k* forward in a manner at once obvious.

I do not limit myself to the specific details of construction herein shown and described, as I believe it is broadly new with me to cause Morse or analogous telegraphic characters to be transmitted or reproduced over an electrical circuit through the agency of a circuit-closer, which is drawn forward and held closed by an embossed transmitting fillet or strip, and I desire it understood that my claims are of such scope as to include any apparatus by which this closure is effected through the agency of a drawing motion in contradistinction to a lifting motion such as I have disclaimed in the prior part of this application.

I am aware that it is old in the art of telegraphy to cause variations in an electrical current passing through a conducting-arm resting on a rotary conducting-cylinder, to give to such conducting-arm a variable to-and-fro motion, and that such an apparatus is known in the art as a "motograph relay," and I make no claim to any construction which does not contemplate the use of an embossed or indented transmitter in combination with a circuit-closer, which has given to it a dragging motion by the embossments or elevations on such transmitter.

Having thus described my invention, what I claim, and desire to secure by Letters Patent of the United States, is—

1. A telegraphic transmitter having raised Morse or equivalent characters on a movable part, in combination with a pivoted transmitting-arm located substantially at right angles to the direction of motion of the movable part, and electrical connections, as described, whereby the characters are accurately reproduced electrically, substantially as described.

2. A transmitter having a recorded code on a moving part, a moving contacting part carrying an electrical contact, said contacting part having to-and-fro motion only in the direction of the part which carries the code, and electrical connections between said parts and an electrical generator, whereby the recorded code is accurately reproduced electrically, substantially as described.

3. An instrument for accurately reproducing Morse or analogous telegraphic characters, consisting of a movable prepared embossed or indented record, a conducting transmitting part having to-and-fro motion in the direction of the movable record, and electrical connections between the conducting transmitting part and a generator of electricity, substantially as described.

4. An instrument for reproducing Morse or analogous telegraphic characters, consisting of an embossed or indented fillet or tape, a transmitting conducting-arm pivotally secured at substantially a right angle to the direction of motion of said tape, but having frictional bearing thereon, and circuit-connections between the arm and an electrical generator, substantially as described.

5. An instrument for electrically reproducing Morse or analogous telegraphic characters, consisting of an embossed or indented fillet or tape, a moving conducting part having frictional bearing on said tape in the direction of the forward motion thereof, with a retracting device and electrical connections between the moving conducting part and an electrical generator, substantially as described.

6. An instrument for reproducing Morse or analogous telegraphic characters electrically, consisting of an embossed or indented tape or fillet, a contacting transmitting-arm pivotally secured at substantially a right angle to the tape, with its free end resting closely thereto, an electrical contact near the free end thereof, a fixed contact against which the first-named contact can move, and electrical connections, as described.

7. A hinged paper guide or arm, in combination with a guiding-roll and a brake-spring, substantially as described.

8. The combination of the hinged paper-guide, the pivoted contacting arm, the guide and feed rolls, and electrical connections between the pivoted arm and an electrical generator, substantially as described.

9. An instrument designed for learners' use, consisting of an embossed record fillet supported by a guiding-arm, a pivoted arm located at substantially right angles to said fillet, its free end adapted to be carried forward by the embossments thereon, in combination with front and back contact-stops, and an adjustable retractile spring attached to the movable arm, substantially as described.
